UNITED STATES PATENT OFFICE.

MICHAEL H. HENESEY, OF SYRACUSE, NEW YORK.

SHINGLE CUTTER.

Application filed August 31, 1922. Serial No. 585,876.

To all whom it may concern:

Be it known that I, MICHAEL H. HENESEY, of Syracuse, in the county of Onondaga, in the State of New York, have invented new and useful Improvements in Shingle Cutters, of which the following, taken in connection with the accompanying drawings, is a full, clear, and exact description.

This invention relates to a portable machine for cutting asbestos shingles and analogous uses in which the relatively moving shearing members and operating means for the movable member, are mounted in opposite hollow heads, or housings, for guiding and stiffening purposes.

The main object is to provide a sturdy, portable device of this character in which the various pivotal pins connecting the relatively movable parts are held against end-wise displacement by the walls of the end housings, and to utilize said housings as means for guiding and protecting the movable parts against contact with external objects.

Another object is to simplify the construction in such manner as to reduce to a minimum the number of pivotal pins required for the operation of the movable shearing member and at the same time to enable the various parts to be easily and quickly detached one from the other and reassembled so that the various parts of the entire apparatus may be packed into compact space for storage or transportation, ready for assembling at any time.

Other objects and uses relating to specific parts of the device will be brought out in the following description:

In the drawings:

Figure 1 is a top plan of a shingle cutting device embodying the various features of my invention.

Figure 2 is a longitudinal vertical sectional view of the same device taken on line 2-2, Figure 1.

Figure 3 is a horizontal sectional view taken in the plane of line 3-3, Figure 2.

Figures 4, 5 and 6 are transverse sectional views taken in the planes of lines 4-4, 5-5 and 6-6, Figure 2.

As illustrated, this device comprises a pair of hollow upright end heads -1- and -1', lower and upper connecting bars -2- and -3-, a movable shearing bar -4-, and suitable operating means for the

shearing bar, consisting in this instance of opposite pairs of link levers, -5-, and a connecting bar -6-, having an extension -7-, connected to the short arm -8- of a bell crank lever which is pivoted at -9- to the end head -1-, and is provided with a handle -10- by which it may be moved about the axis of its pivot -9.

The end-heads -1- and -1'- are provided with guide chambers -11- in their inner upright sides, facing each other, and communicating at their lower ends with horizontal branch chambers -12-, which extend through the front faces of the end heads or brackets -1- and -1'- to form guide openings for the ends of the connecting bar -2-.

The outer, upright end walls of the brackets -1- and -1'- are closed and form abutments for the ends of the shearing bars -2-, the lower ends of said brackets being also closed to form flanged seats -13- upon which the ends of the lower bar -2- rest.

The front and rear walls of the chambers -11- of the brackets -1- and -1'-, above the branch openings -12- are substantially parallel and constitute guides for holding the movable parts against lateral or forward and rearward movement, the rear wall being extended to the base -13- to hold the bar -2- against rearward displacement, except for the slight adjustment which may be necessary to bring said bar into proper shearing relation to the movable bar -4-.

The lower ends of the rear sides of the brackets -1- and -1'- are provided with rearwardly projecting flanges -14-, having bolt openings for receiving bolts or screws -15-, by which the brackets may be secured to a supporting base as -16-.

Suitable angle braces -17- are arranged across the front sides of the branch openings -12-, and are provided with forwardly projecting flanges, as -14'-, having bolt openings for receiving bolts or screws -15'-, adapted to be secured to the base -16-.

The ends of the bar -2- which project into the branch openings -12- and lower ends of the vertical guide chambers -11- are provided with transverse bolt openings -18- registering with similar openings in the rear walls of the chambers -11-, and upright wall of the braces -17- for re-

ceiving bolts —19—, by which the bar is rigidly secured in place to the brackets —1— and —1'—, and which also serve to secure the braces —17— to the front sides 5 of the bar —2—. Additional bolts —19'— secure the ends of the bar —2— to the offset portions of the brackets —1— and —1'—.

The ends of the bar —2— are therefore 10 rigidly held in the lower ends of the brackets —1— and —1'— between the braces —17— and rear walls of said brackets, but the bar may be removed by forward displacement from the branch openings —12— by simply 15 removing the bolts —19— and —19'— and screws —15'— which permit the forward displacement of the braces —17—, thus releasing the bar —2— for forward displacement.

20 The bar —2— is somewhat L-shaped in cross section, forming an upper longitudinal rib having its inner face beveled to form a knife edge —20— for shearing cooperation with a similar knife edge —21— on the bar 25 —4—. That is, the longitudinal rib having the knife edge —20— is disposed at the front side of the vertical guide chamber —11— and is relatively broad transversely to resist lateral springing, while the vertical 30 thickness is sufficient to prevent vertical springing of the knife edge, all of which adds materially to the cutting efficiency of the device.

35 The ends of the movable shearing bar —4— are of substantially the same width as, and are guided in the upright chambers —11— of the brackets —1— and —1'—, the upper edges thereof being reduced to form lugs —22— for receiving the lower link arms 40 —5—.

45 The shearing edge —21— is formed upon the lower front corner of the bar —4—, which is guided in its vertical movement by the front and rear walls of the chambers —11—, to cause the shearing edge —21— to move in the vertical plane of the shearing edge —20— of the lower bar —2—, for shearing purposes, the rear side of the bar —4— being reinforced by a rib, to reduce 50 the liability of springing of the intermediate portion of the bar during the shearing operation.

55 The upper bar —3— is parallel with the lower bar —2— and has its opposite ends bifurcated to receive the upper ends of the upper link arms —5—, and are of just sufficient transverse width to fit easily between the opposite upright walls of the guide chamber —11—, and are secured to said side walls by bolts —23—, which are also passed through registering apertures in the adjacent upper ends of the link arms —5— to pivotally connect said arms to the adjacent ends 60 of the bar —3— and also to the side walls 65 of the brackets —1— and —1'—.

The lower ends of the lower link arms —5— are also bifurcated to receive the lugs —22— on the opposite ends of the bar —4—, and are hinged thereto by pivotal pins —24—, which are held against endwise displacement by the side walls of the brackets —1— and —1'—. 70

The bar —6— is disposed between and parallel with and between the lower and upper bars —2— and —3—, and also between the bars —3— and —4—, and has its opposite ends bifurcated to receive the adjacent ends of the link arms —5— of each bar.

That is, the adjacent ends of the link arms 80 of each bar are reduced in thickness to overlap one upon the other, and are pivoted to and between the opposite arms of the adjacent bifurcated end of the bar —6— by a pivotal pin —25—, which is held against 85 endwise displacement by the side walls of the brackets —1— and —1'—.

The extension —7— of the bar —6— is also bifurcated to receive the adjacent reduced end of the arm —8— of the bell crank 90 lever, which is pivoted at —9— to and between the opposite sides of the adjacent bracket —1—, to swing vertically, the chamber —11— of the bracket —1— being continued through the upper end of said bracket, to allow free swinging movement of the bell crank lever in the operation of the connecting bar —6— and link arms —5— for raising and lowering the movable shearing bar —4—. 100

The longer arm, or handle —10—, of the bell crank lever, extends above the upper end of the adjacent bracket —1—, to overhang the intermediate portion of the device, with sufficient clearance to allow it to be 105 moved vertically the necessary distance to open and close the movable shearing bar —4—.

The shorter bar —8— of the bell crank lever, is connected to the bifurcated extension —7— by means of a pivotal pin —26— which is held against endwise displacement by the side walls of the bracket —1—. 110

It will be observed that the adjacent ends of each pair of link arms is connected to the bar —6— by a single pivot, and that all of the movable pivots, as —24—, —25— and —26— are held against endwise displacement solely by the side walls of the brackets —1— and —1'— without extra fastening means such as nuts, cotter keys and analogous devices. 115

By removing the bolts —19— and —19'—, and braces —17—, the lower bar —2— may be readily withdrawn forwardly through the front, open side of the branch chambers —12—, in case it should become necessary to sharpen the cutting edge —20— or for any other purpose. 125 130 135

By removing the pivotal bolts —9— and —23—, the brackets —1— and —1'— may be removed, thus permitting the upper bar —3—, shearing bar —4— and its operating means, including the bar —6—, link levers —5— and bell crank lever to be detached by simply removing the pivotal bolts 24, 25 and 26, which allows the various disassembled parts to be packed in compact space, for storage or transportation, and also allows the shearing bar —4— to be resharpened and other repairs to be made if necessary.

The upper bar —3— is provided with shoulders —30— for engaging the inner edges of the upper portions of the brackets —1— and —1'— to assist in holding the latter in fixed spaced relation and thereby to stiffen the device as a whole when the parts are assembled for use.

The movable shearing bar —4— is provided with guide lugs —31— in sliding engagement with the inner upright edges of the brackets —1— and —1'— to hold said bar against endwise movement and also to guide it in its vertical movement.

If desired, one or more thin shims —32— may be inserted between the rear edges of the ends of the bar —2— and rear wall 30 of the brackets —1— and —1'— to allow for slight adjustment of said bar as may be necessary for proper shearing cooperation with the bar —4—.

What I claim is:

35 1. In a shingle cutter, a frame including guide chambers at the opposite ends there-

of, cooperating shearing bars movable one in relation to the other and having their adjacent ends projecting into said guide chambers, a pair of link levers housed within each guide chamber and pivotally connected to one of said shearing bars, an operating bar pivotally connected to said link levers, an operating lever pivotally connected to said frame and projecting into one of said guide chambers, and a pin and slot connection between said operating lever and said operating bar, the said pivotal connections between said link levers, operating bar, operating lever, and movable shearing bar consisting of loose pins which are retained in operative positions by the walls of said guide chambers.

2. In a shingle cutter, a frame including hollow upright end heads, a pair of link levers housed within each hollow head, a movable shearing bar having its ends connected to the link levers within said end heads, an operating bar connecting said link levers and an operating lever pivotally connected to one of said hollow heads and projecting into the same for pivotal connection with said operating bar, whereby said hollow upright ends will protect the aforementioned pivotal connections during the operation of the device.

In witness whereof I have hereunto set my hand this 4th day of August, 1922.

MICHAEL H. HENESEY.

Witnesses:

HARRY E. FULLERTON,
J. O. McGINNIS.
